Specification for Design.

Patented Nov. 1, 1921

Application filed August 24, 1921. Serial No. 495,107. Term of patent 3½ years.

To all whom it may concern:

Be it known that I, THOMAS W. ESTES, Jr., a citizen of the United States of America, residing at Brooklyn, Kings county, State of New York, have invented a new, original, and ornamental Design for a Textile Fabric, of which the following is a specification, reference being had to the accompanying drawing, forming part hereof, in which the figure illustrates a face view of a piece of textile fabric, having my new design.

I claim:

The ornamental design for a textile fabric, as shown.

Signed at New York city, N. Y., this 19th day of August, 1921.

THOMAS W. ESTES, JR.
